his Attorney.

UNITED STATES PATENT OFFICE.

EDGAR E. STOCKWELL, OF LOS ANGELES, CALIFORNIA, ASSIGNOR TO O'BRIEN MERRILL,
INCORPORATED, OF LOS ANGELES, CALIFORNIA, A CORPORATION OF NEVADA.

COMBINATION-CHAIR.

1,244,389.

Specification of Letters Patent. Patented Oct. 23, 1917.

Application filed March 13, 1916. Serial No. 83,806.

To all whom it may concern:

Be it known that I, EDGAR E. STOCKWELL, a citizen of the United States, residing at Los Angeles, in the county of Los Angeles, 5 State of California, have invented new and useful Improvements in Combination-Chairs, of which the following is a specification.

This invention relates to chairs, and the 10 like; and it is a particular object of this invention to provide a combination device which may be adjusted to a variety of positions to provide, for instance, a chair, rocking chair, a reclining chair, a couch, etc. 15 And it is an object of this invention to provide such a device in light, strong and simple form, easily and simply operated and adjusted, and sightly in appearance.

The subject matter of the present application 20 and a companion application S. N. 83,805 filed March 13, 1916, comprise the whole assembled device which includes a chair, couch, lounging chair combined with a book rest or desk. The adjustments for 25 changing the position of parts of the chair, to suit comfort of the user, are so placed that the position of the parts, say of the back or foot rest, may be changed with ease while the user is sitting in the chair. The 30 book rest or desk may be adjusted to any position by the user without rising. A small light is placed on the desk for night reading and in the whole device there is included everything necessary for the comfort 35 and convenience of the user.

In its preferred form my device embodies a base and a rocker frame thereon, means being provided for setting the rocker frame in any desired position. Back and foot 40 frames are pivoted to the rocker frame, or to the seat frame formed in the upper part of the rocker frame. The back frame may be supported at any desired angle, as may also the foot frame. Various other adjustments 45 are provided.

The various features of my invention will be best understood from the following description of a preferred form of device embodying the invention, reference being had 50 to the accompanying drawings in which I have shown said preferred form of device. In these drawings Figure 1 is a side elevation of my improved device in one of its many positions. Fig. 2 is a horizontal plan section taken as indicated by line 2-2 on

Fig. 1; Fig. 3 is a vertical central section showing the device as in another one of its positions, Fig. 4 is a horizontal section taken as indicated by line 4-4 on Fig. 3, both Figs. 2 and 4 showing the device without 60 the upholstery cushions which are shown in Figs. 1 and 3, Fig. 5 is a sectional view showing a modification of the base of my device, and Fig. 6 is a section taken as indicated by line 6-6 on Fig. 2. 65

In the drawings I have shown a suitable base 10 mounted upon rollers or casters 11. In the drawings I have shown these casters of the ordinary small size; but larger rollers or wheels may be substituted so as to make 70 my chair particularly adapted for use as an invalid chair to be easily wheeled about. This variation, and other variations, in the structure will be referred to hereinafter.

The base 10 has upper longitudinal surfaces 75 12, forming rolling surfaces for the rockers 13. Rockers 13 form part of side frames 14 having upper horizontal members 15, one on each side of the chair. The horizontal members 15 are curved upwardly at their front 80 and rear ends, as shown at 15a, and carry the pivots 16 and 17. The back frame 18 of the chair is pivoted to the pivot 17, while the foot frame 19 is pivoted to the pivots 16.

The foot frame 19 is normally folded back 85 over and within the side frame members 15, as is illustrated in Figs. 3 and 4; but when the foot frame is in use it is thrown outwardly to such a position as is illustrated in Figs. 1 and 2; and is then supported by 90 the foot supporting brace frame 20. This foot supporting brace frame 20 is pivoted at 21 to the foot frame 19 and has on its free end lugs or projections 22 which engage in ratchet teeth 23 formed on the inner 95 faces of rockers 13. Adjustment of the position of foot frame 19 may be easily made by raising the brace frame 20 and raising or lowering the foot frame to the desired position. In Fig. 1 the foot frame is shown 100 extending approximately on a line with the frame members 15; but the foot frame may be either raised from this position or lowered considerably, to support the user's feet and legs in any desired position.

At the forward end of the foot frame I provide a small end frame 25, pivoted to the foot frame at 26 so that it may be thrown down flatly on the foot frame, to the position shown in Fig. 3. This end frame is so situ- 105 110

ated as to form a rest against which the occupant's feet may be placed; and it has parts 25^a under and into which the heel or heels of the shoe may be inserted to lift the 5 foot frame upwardly to adjust its position, either up or down. For instance, if it is desired to lower the foot frame, it is only necessary to insert the heel in end frame 25 and raise the foot frame so as to raise its 10 weight off the brace frame 20, and then lift brace frame with the other foot, lower the foot frame to the desired position and then drop the brace frame, when the lugs 22 will drop into the ratchets 23 and hold the foot 15 frame in the desired position. This may all be accomplished without using the hands at all.

The back frame 18 is pivoted at 17 to the side bars 15, as hereinbefore stated. This 20 back frame normally stands, when the device is used as a chair, in or near a vertical position. A supporting frame 30 is pivoted at 31 to the back frame, said supporting frame having a cross bar 32 near its lower 25 end. This supporting frame is turned at right angles to the back frame and becomes the support for the back frame when the back frame is laid down to the position indicated in dotted lines in Fig. 1. It will be 30 understood that the back frame may be thrown from a vertical to a horizontal position, being in or near the vertical position when the device is used as a chair, in an angular position when the device is used as a 35 reclining chair, and in a horizontal position when the device is used as a couch. When used as a chair the supporting frame 30 is used as a means for holding the cushion 33, which cushion is the one placed on the foot 40 frame 19 when the foot frame is extended as shown in Fig. 1. The back frame and foot frame are provided with interior wooden frames 18^a and 19^a, respectively, which frames may have facings of ratan or 45 the like, as indicated at 18^b and 19^b, these frames forming the supports for the upholstery cushions. There is also an interior wooden frame 15^a with ratan or other fac- 50 ing 15^b secured in the frame formed by the two side members 15 and cross members 15^c. The cushion 34 is placed upon the interior wooden frame 15^a when the device is in the 55 position shown in Fig. 1, and placed upon the interior wooden frame 19^a when the device is in the position shown in Fig. 3. The frame 19^a has ratan or other facings on both its sides, so that, whichever side of the frame is uppermost, there will be a smooth frame facing upon which to place the seat cushion 60 34. The back cushion 35 is made to conform to the back frame. When the device is completely extended, used as a couch, the three cushions are all in use; but when used as a chair, the foot frame cushion is held 65 behind the back, as hereinbefore described.

The means for holding the back frame up in any desired position will now be described. Arms 40 are pivoted at 41 to back frame 18 and are pivoted at their forward ends at 42 to curved levers 43 which are pivoted at 44 to the members 15. A brace frame 46 is pivoted to the levers 43 at 45, consisting of side bars 47 and a horizontal connecting bar 48 below the members 15. The brace bars 46 have lugs or the like, 49, 70 which engage with ratchet teeth 50 on the side members 15. These ratchet teeth are covered by shields 51 to protect the apparel from being caught in the ratchet teeth. A small handle 52 is provided so that the occupant, sitting in the chair, can raise the ratchet frame 46 and then move the back frame to any desired position, allowing the ratchet frame to again fall and engage the ratchet teeth 50 to hold the back in the desired position. It will be noticed that arms 40 move with the back; and, when the back has been moved down to the position indicated by dotted lines in Fig. 1, then the arms 40 have moved down to a position where 80 they are almost or quite completely below the cushions on the bottom and back frames; so that the device then becomes a couch with no part projecting above the upper surface of the cushion. In the extreme horizontal position of the back frame, the ratchet frame 46 does not entirely leave engagement with the ratchet teeth 50, but the lugs 49 ride on the last tooth surface 50^a; so that, when 85 it is desired to again raise the back frame, it is not necessary to reengage the lugs 49 with the ratchet teeth 50. Ordinarily the back cannot be moved forward, or cannot fall forward, from its vertical position, due to the lugs 49 catching under projections 50^b at the 90 forward end of ratchet teeth 50. But the back can be folded down flat on the seat by raising the brace frame 46 so as to raise lugs 49 over the projections 50^b. The chair, thus 95 folded, occupies but a very small space, and can be easily packed for shipping purposes or put in an automobile for camping use.

I have previously referred to the rockers 13 resting upon the surfaces 12 of the bottom frame 10. On each side of the bottom frame I provide a curved or sector-shaped guide 60; and the rockers 13 have a transverse rod 61 which passes through these guides 60. The rod 61 screws into one of the rockers at one end, as shown at 62. On the 115 rod between the guides 60 there is a spacer sleeve 63; and on the outside of the other rocker there is a collar 64 on rod 61. A handle 65 provides for turning the rod to screw or unscrew it. When the rod is screwed up 120 tightly the rockers are held tightly against the guides 60, so that the whole chair may be rigidly set in any position desired, either horizontally or at any desired angle. When 125 the rod 61 is loosened, then the chair is free 130

to rock upon the surfaces 12. I provide springs 65 to limit the rocking motion and to give a certain resilient action.

Now, I may provide means for rocking 5 the chair mechanically; as by providing a small motor 70 which operates a crank 71 connected by connecting rod 72 to the frame of the chair at any convenient point. A switch 73 may be mounted upon the chair 10 at any convenient point, as on one of the arms 40, for controlling the motor 70.

In Fig. 5 I have shown a variation wherein the bottom or base frame 10^a is provided with large rubber tired wheels 11^a, so that 15 the chair may be easily rolled as an invalid chair, or the like. And I may also provide on the chair, whether the large wheels are used or not, a device such as illustrated in Fig. 5 for holding the chair immovable.

20 This may embody such an arrangement as a rod 80 having feet 81 with rubber tips. The rod and its feet are moved vertically, guided by bearing 83 by a small crank 84 operated by handle 85 at one side of the 25 chair. Any suitable means may be employed to hold the crank and handle in either of their positions.

A clamp 100 is shown attached to member 15 which is adapted to hold a book rest, etc., 30 which is the subject matter of a companion application, S. N. 83,805 filed March 13, 1916. The book rest is so attached as to rock with the chair and keep in the same relative position to the user.

35 Having now described a preferred form of device embodying my invention, it will be seen that my invention provides an adjustable mechanism which may be put into position for a great variety of uses. And it will 40 be further noticed that changes in the positions of the various parts may be easily made by the occupant without rising from the chair. The various parts of the chair are all so balanced that they are easily movable; and the device as a whole is extremely 45 strong and rigid, in spite of the fact that it is of light construction.

Having described the preferred form of my invention, I claim:

50 1. In combination, a base, a rocker frame

adapted to rock on said base, a back frame pivoted to the back end of said rocker frame, a foot frame pivoted to the forward end of said rocker frame, means for adjustably supporting the back frame and for adjustably supporting the foot frame, said back frame being adapted to be thrown backwardly and downwardly to a horizontal position and to be thrown forwardly and downwardly to a horizontal position over the rocker frame 60 and said foot frame adapted to normally fold back and down over the rocker frame and adapted to be thrown forwardly and outwardly to extend forwardly from the rocker frame, and manually releasable means 65 for normally preventing the back frame from moving forwardly past an approximately vertical position.

2. In a device of the character described, a seat frame and supporting means therefor, 70 a back frame pivoted to the rear end of the seat frame so as to swing forwardly onto said seat frame, means to adjustably support the back frame, and manually releasable means to normally prevent the forward 75 movement of the back frame forwardly of an approximately vertical position.

3. In a device of the character described, a seat frame and supporting means therefor, 80 a back frame pivoted to the rear end of the seat frame, means to adjustably support the back frame, said means including a brace frame composed of two brace arms and a horizontal tie rod and including horizontal ratchet teeth on the seat frame adapted to be 85 engaged by the brace arms, there being an overhanging hook at one end of the ratchet teeth adapted to be engaged by the brace arms when the back frame is in approximately vertical position to normally prevent 90 the back frame being moved forward of said position.

In witness that I claim the foregoing I have hereunto subscribed my name this 7th day of March 1916.

EDGAR E. STOCKWELL.
